US00D961410S

(12) **United States Design Patent** (10) **Patent No.:** **US D961,410 S**
(45) **Date of Patent:** **** Aug. 23, 2022**

(54) **SMART HYGIENE DEVICE**

(71) Applicant: **Willo Technologies, LLC**, Pasadena, CA (US)

(72) Inventors: **Sean M. Podvent**, Pasadena, CA (US); **Richard Adams**, Los Angeles, CA (US); **Aleksandar Bradic**, Palo Alto, CA (US); **Vojislav Antonic**, Pasadena, CA (US)

(73) Assignee: **HYGIENE IQ, LLC**, Los Angeles, CA (US)

(**) Term: **15 Years**

(21) Appl. No.: **29/741,286**

(22) Filed: **Jul. 10, 2020**

(51) LOC (13) Cl. **10-03**

(52) U.S. Cl.

USPC **D10/40**; D14/488; D24/186
